UNITED STATES PATENT OFFICE.

JOHN H. DEAN, OF BIRMINGHAM, ALABAMA.

BUTT-JOINT NESTABLE CULVERT.

1,238,274.

Specification of Letters Patent. Patented Aug. 28, 1917.

Application filed October 30, 1913. Serial No. 798,263.

To all whom it may concern:

Be it known that I, JOHN H. DEAN, a citizen of the United States, residing at Birmingham, in the county of Jefferson and State of Alabama, have invented certain new and useful Improvements in Butt-Joint Nestable Culverts, of which the following is a specification, reference being had therein to the accompanying drawing.

10 This invention relates to means for fastening together and maintaining in abutting relation the longitudinal edges of my improved butt-joint metal culvert, said means comprising keys or clips and their co-operating 15 key-receiving sockets or passageways, which sockets or passageways are formed upon the culvert along the longitudinal edges thereof.

The principal object of the present invention resides in an improved method of forming the key receiving sockets or passageways, and in this connection it is to be noted that the metal stock of the culvert itself is utilized for this purpose, and without the use 25 of metal strips or bars welded or riveted to the culvert as set forth in Patent No. 1,049,816, granted to me January 7, 1913.

Further objects and advantages will appear in the following description, it being understood that various changes in form, proportions and minor details of construction may be resorted to within the scope of the appended claims.

I have illustrated my invention in the accompanying drawings, in which:

Figure 1 is a side elevation, partly broken away, of a butt-joint culvert illustrating my improved fastening means, the same intending to illustrate a culvert of this type made 40 up of complementary half sections;

Fig. 2 is a plan view, partly broken away, of a lower complementary half section, the same illustrating keys or clips engaging within the passageways formed at the longitudinal edges of the section, the keys being shown in cross section;

Fig. 3 is a partial transverse sectional view of the culvert taken on the line 3—3 of Fig. 1, and

50 Fig. 4 is a perspective view of one of the keys.

Referring to the drawing, it is to be noted that each section indicated at 1, of the butt-joint culvert is shown provided with corrugations which are arranged parallel with opposite ends thereof, and that when these

sections, which are preferably half sections, are arranged in assembled position to form the completed culvert, the corrugations of upper and lower sections coincide with each other, or in other words, each convex and concave corrugation of an upper section is directly in line with the convex and concave corrugations respectively of the section below it. It is to be noted that these sections 60 are constructed without the usual outstanding flanges, and that the longitudinal edges of complementary sections are adapted to abut as indicated at 2 in the drawing, so that when said sections are connected together with their longitudinal edges meeting or abutting, the corrugated culvert, for all intents and purposes, has the appearance and strength of an integral corrugated cylinder.

In the type of culvert just referred to, key-receiving sockets or passageways 3 are formed at intervals along the longitudinal edges of the culvert sections, the key-receiving sockets along the longitudinal edge of one section co-operating with those along an adjacent longitudinal edge of a complementary section, so that a key such as indicated at 4, engaging within co-operating key-receiving sockets of adjacent longitudinal edges will serve when properly applied, to securely hold and retain said longitudinal edges in connected relation.

As has heretofore been referred to, it is the purpose of this invention to form the key-receiving sockets from the metal stock of the culvert itself, and this is done by forcing out by a spinning or other preferred operation, portions of said metal stock along the longitudinal edges of the culvert sections, thereby forming protuberances 5 which project in a direction longitudinally of the culvert. Two of these projections or protuberances are provided for each key-receiving socket, the same projecting in opposite directions longitudinally of the culvert, or in other words, said projections extending toward each other. It will therefore be seen that the body of the culvert situated between each pair of projections 5, and the projections 5 themselves constitute a pocket or passageway for receiving the key 4 as above referred to.

In the preferred embodiment of the invention, these projections 5 are formed by spinning the same from adjacent convex corrugations, so that said projecting por-

tions extend over and partially close the concave corrugation which is situated between said adjacent convex corrugations, as clearly shown in the drawing.

5 In assembling the culvert sections with their longitudinal edges abutting, the keys or clips are inserted within coöperating sockets or passageways until the downwardly extending flange 6, formed upon the upper 10 end of the key, engages the projections 5 upon the upper section, and as will be readily understood, the lower portion 7 of the key, which, in this position, extends below the projections upon the lower section, may 15 be bent up into engagement with said last mentioned projections, thus completing the joint.

While this invention has been shown and particularly described in connection with a 20 corrugated culvert, it is to be understood that said invention is not limited thereto, as it will be perfectly obvious that these key-receiving sockets or passageways may be formed upon smooth or flat surfaced cul- 25 verts.

Having thus described my invention, what I claim and desire to secure by Letters Patent is:—

1. Fastening means for connecting together the longitudinal edges of butt-joint culverts, comprising a projecting portion or bulging protuberance spun from the side of said culvert and projecting in a direction longitudinally of the culvert, and a key coöperating with said projecting portion.

2. Fastening means for butt-joint culverts, comprising pairs of projecting portions formed from the metal stock of said culvert along a longitudinal edge thereof, 40 and arranged to project toward each other to form a key receiving socket, and a key coöperating with said projecting portions.

3. Fastening means for connecting together the longitudinal edges of butt-joint culverts, comprising coöperating key-receiving

50 sockets or passageways formed from the metal stock of the culvert and arranged along each longitudinal edge, and a locking key engaging within coöperating passageways, said key being moved in a direction transverse to the culvert during the insertion of the same within coöperating passageways.

4. Fastening means for butt-joint corrugated culverts, comprising coöperating key-receiving sockets or passageways, said passageways formed by spinning from adjacent convex corrugations projecting portions which extend over and partially close a concave corrugation, and a key engaging within 60 said coöperating passageways.

5. Fastening means for butt-joint culverts, comprising projecting portions or protuberances spun from the culvert stock itself, said protuberances adapted to extend 65 toward each other and in a direction longitudinally of the culvert, and a locking key coöperating with said protuberances.

6. A culvert having abutting longitudinal edges adapted to be connected together, 70 and key-receiving sockets or passageways formed from the metal stock of said culvert and arranged along each longitudinal edge, the passageways of abutting longitudinal edges coöperating one with the other, and forming continuous passageways for receiving locking keys.

7. A corrugated metal culvert having projecting portions extending in opposite directions from adjacent convex corrugations, 80 said projections together with the concave corrugation situated between said convex corrugations, forming a key-receiving socket or passageway.

In testimony whereof I have affixed my 85 signature in presence of two witnesses.

JOHN H. DEAN.
